UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,515, dated October 11, 1881.

Application filed August 9, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a large rosette. Below it are two connected rosettes, B B, set in a branch having leaves. To the right of these is a cross-shaped figure, C, having a rosette, a, at its lower end and a part of a rosette, b, near the upper end. A branch connects the figure C with a figure, D, which appears to be made up of superposed rosettes, and from which projects a branch, d, with three floral projections. Above figure D is the figure E, composed of overlapping rosettes set in a branch. Below figure D, somewhat to the left, is a figure, F, composed of a square, which is flanked by rosettes and leaves. G is a large star-shaped figure with a small rosette at one side. H is a round figure capped with a crown-like ornament, e, above which is part of a rosette, f. At the left figure H connects with a square figure, g, having round projections on three sides. Above the figure g is the large richly-embellished rosette I, from which project sundry leafed branches that unite

it to the other figures. Between figures B and I is the figure J, composed of rosettes and of a fan-shaped central ornament. The two stems reaching contact with figure J are not part of said figure. To the right of figure I is a floral ornament, K, growing on a stem that projects from the figure C. Below figure K is the group L, composed of a rosette with leafy projections. Below the figure H is the figure S, composed of rosettes and leaves. Below figure S is figure M, of fanciful outline. To the right of figure M is figure N, a square with fan-like projections. The figure O, to the right of figure N, resembles a butterfly in outline. The figure P below is a large and much embellished rosette. Q is a figure made up of superposed rosettes. The figure R is cross-shaped and flanked with rosettes. All these figures and many of lesser importance are set in leaves and buds, and together make up a rich decoration for the carpet.

Interspersed between the figures are clouds composed of hexagons, which, though constituting connecting-links for the figures, still leave the outline of each distinct and clearly discernible.

I claim—

The design for carpets, consisting of the figures A B C D E F G H I J K L M N O P Q R S a b d e f g, substantially as shown.

WINTHROP L. JACOBS.
